UNITED STATES PATENT OFFICE.

HERVEY W. FOWLER, OF CHICAGO, ILLINOIS.

MACHINE FOR ROLLING CAR-WHEELS.

SPECIFICATION forming part of Letters Patent No. 715,777, dated December 16, 1902.

Application filed July 8, 1902. Serial No. 114,201. (No model.)

To all whom it may concern:

Be it known that I, HERVEY W. FOWLER, a citizen of the United States, residing at Chicago, in the county of Cook and State of Illinois, have invented new and useful Improvements in Machines for Rolling Car-Wheels, of which the following is a specification.

In United States Letters Patent No. 394,565, granted to me December 18, 1888, I show and describe a machine for rolling car-wheels from cast-steel blanks, which have a hub in its desired or finished form, a web of the desired thickness in the finished wheel, and a rim which is thicker than is desired in the finished wheel and having a rudimentary flange, said machine operating to develop the rudimentary flange into perfect form and reduce the thickness of the rim for producing a cast-steel wheel having the metal of the hub and web in its normal condition and the metal of the rim and flange condensed in radial and peripheral lines. The wheels produced by said machine are slightly larger in diameter than the blank from which they are rolled and possess peripheral inaccuracies or variations which render it necessary to subject the wheel to the action of a truing-machine—such, for instance, as disclosed in United States Letters Patent No. 351,430, granted to me October 26, 1886—the latter machine operating by rolling action to slightly reduce the diameter of the wheel by further condensing the metal of the rim and correcting such peripheral variations as may exist therein.

The main object of my present invention is the production of a machine capable of performing the rolling operation described in my aforesaid Letters Patent No. 394,565, as well as the truing operation described in my aforesaid Patent No. 351,430.

To this end my invention, broadly stated, consists in the combination of three or more positively-driven tread-working rolls having working faces corresponding to the tread and flange of a finished car-wheel, a pair of rim-supporting rolls for supporting the rim of a wheel at the two sides of its web against the thrusting action of one of said tread-working rolls, and means whereby the relative position of the tread-working rolls and the rim-supporting rolls may be shifted for permitting the rim of a wheel-blank to be rolled between

said rim-supporting rolls and one of said tread-working rolls and thereafter between all of said tread-working rolls away from the 55 action of said rim-supporting rolls.

After a detail description of a machine embodying my invention the features deemed novel will be specified in the claims hereunto annexed.

Referring to the drawings furnished and forming a part of this specification, Figure 1 illustrates in partial longitudinal vertical section a machine embodying my invention, a car-wheel being shown therein in the position 65 it occupies during the initial rolling operation. Fig. 2 is a vertical lateral section of said machine; and Fig. 3 is a section on the line $x-x$ of Fig. 1, showing the driving-gears.

The main frame or housings may be of any 70 form which will afford suitable bearings and supports for the several working parts of the machine. As shown in the drawings, said frame consists of uprights or standards A, A', A², A³, A⁴, and A⁵. The working rolls are 75 located between the standards A and A'. The main tread-working roll B is supported by a yoke or carriage C, which moves in guides or ways a a' in the uprights A and A', and attached to said carriage is a piston d, which 80 works in a hydraulic cylinder D, the latter operating to move said carriage and apply the necessary pressure to the roll B, as will be understood. The casting forming the cylinder D also serves to unite the upper ends of 85 the standards A and A', said casting being bolted to the standards, as clearly shown in Figs. 1 and 2.

The roll B has a working face conforming at b with the tread of the desired car-wheel, 90 and at b' it has a groove which conforms to the flange desired in the finished wheels. At the ends of said working face there are annular vertical faces b² b³, which confine or restrict the metal in the rim of the blank against 95 lateral expansion. Said roll is provided with a shaft b⁴, mounted in suitable bearings in the arms c and c of the carriage C, said shaft being positively driven by means of flexible connections from gearing to be hereinafter 100 referred to.

Mounted between the standards A and A' at the base of the machine is a hydraulic cylinder E, having a piston e, to which is at-

tached a carriage F, the latter being guided by and between the two standards and having its ends f and f projecting laterally therefrom, as best shown in Fig. 2. Mounted in 5 the ends f and f of the carriage F are two tread-working rolls G and H, which correspond in size and shape to the roll B, before described, and said rolls are positively driven in a similar manner, as will be hereinafter de- 10 scribed. The rim-supporting rolls I and J are mounted at an angle to each other and to the axis of the main tread-working roll B, the axis of each of said rim-supporting rolls being inclined downwardly from their outer to their 15 inner ends and presenting annular working faces i and j directly beneath the roll B. Roll I is supported in inclined bearings i³ and i⁴ in the standards A' and A², and said roll is confined against longitudinal movement by 20 the collars i⁵, i⁶, and i⁷.

Roll J is supported at its inner end in an inclined bearing j³, and its outer end is mounted in a slidable bearing j⁴, to which is attached a piston k, which works in a hydraulic 25 cylinder K, the latter operating to move said roll longitudinally for permitting the insertion and removal of a wheel, as will be explained.

The inner end of the rim-supporting rolls I 30 and J are each provided with a projecting annular working face i and j and a vertical annular face i' and j'. The faces i and j in their sectional contour exactly conform to the contour of the under surface of the rim of a finished car-wheel, and a wheel-blank in position for the initial rolling operation is suspended vertically upon said projecting faces i and j, and the vertical faces i' and j' serve to properly restrict the rim of the blank or 35 wheel against liability of lateral expansion. Because of the angular arrangement of said rolls the end faces i³ and i⁴ do not contact with the web w of the blank or wheel W, said web being thereby left in its original or un- 40 worked condition, and it is to be noted that the space between the two rolls, which is partially occupied by said web, is greater than the thickness of the web, so that said rolls will be entirely free from contact with the 45 wheel or blank when the latter is raised, as 50 hereinafter explained.

Roll I is positively driven from the main driving-shaft L, which is mounted in the standards A⁴ and A⁵, said roll being connected 55 to said shaft by a well-known form of flexible coupling l. On the shaft L, between the standards A⁴ and A⁵, is a gear l², which drives a gear m, the latter meshing with and driving a gear m', which in turn drives two gears n 60 and o, mounted on shafts n' and o'. The rim-working rolls G and H are driven by the shafts n' and o', said rolls being connected to said shafts by flexible couplings p, as illustrated in Fig. 1. The gear l² on the main 65 shaft also drives a gear q on a shaft q', the latter being coupled by a flexible coupling q² for driving the main tread-working roll B.

Gear q on shaft q' drives a gear r, which in turn drives a gear s on a shaft s', which has its bearings in the standards A⁴, A⁵, and A³. 70 On said shaft is a gear t, which meshes with a gear u on the roll J, said gear being so mounted on the roll as to drive the latter and at the same time permit it to be moved longitudinally, a small roller v serving to hold the gear 75 against the longitudinal movements of the shaft, as will be understood.

In the operation of the machine the rim-supporting roll J is drawn outwardly by means of the hydraulic cylinder K, and the carriage 80 C, carrying the roll B, is raised and carriage F, carrying the rolls G and H, is lowered to permit of the insertion of a wheel or blank W, which is placed between the rolls, with its rim resting upon the face i of the roll I. The roll 85 J is then pushed forward for supporting the wheel or blank, as illustrated in Fig. 1. Carriage F is then raised so that the rolls G and H may act as guides for the revolving blank, and after the main tread-working roll B is 90 lowered the machine is put in operation by revolving the main driving-shaft L. During such operation hydraulic pressure is applied to the roll B by means of the cylinder D for causing the rim of the wheel or blank to be 95 compressed between the roll B and the rim-supporting rolls I and J, this initial operation being the same as described in my aforesaid Letters Patent No. 394,565. After the completion of this initial rolling operation the 100 carriages C and F are raised for lifting the wheel away from the action of the rim-supporting rolls, as indicated in dotted lines in Fig. 2. The operation of the machine is then continued while hydraulic pressure is being 105 applied to all of the tread-working rolls by means of the cylinders D and E, the wheel W being then wholly supported by said tread-working rolls while the rim is being rolled and trued, as described in my aforesaid Letters Patent No. 351,430. At the completion 110 of this final rolling operation the finished wheel is removed and another blank inserted, as before described.

Having thus described my invention, what 115 I claim as new, and desire to secure by Letters Patent, is—

1. In a machine for rolling the rims of car-wheels, the combination of three or more tread-working rolls having working faces corresponding to the tread and flange of a finished wheel, a pair of rim-supporting rolls for supporting the rim of a wheel at the two sides of its web against the thrusting action of one of said tread-working rolls, said rim-supporting rolls being so positioned as to prevent the web of the wheel from being rolled thereby, and means for changing the relative positions of the rim-supporting and tread-working rolls without varying the working 125 positions of the latter with respect to each other, whereby the rim of a wheel may be initially rolled between said rim-supporting rolls and one of the tread-working rolls and 130

thereafter rolled between all of the tread-working rolls independently of and away from the action of said rim-supporting rolls, substantially as described.

5 2. In a machine for rolling the rims of car-wheels, the combination of three or more positively-driven tread-working rolls having working faces corresponding to the tread and flange of a finished wheel, a pair of rim-supporting rolls for supporting the rim of a wheel at the two sides of its web against the thrusting action of one of said tread-working rolls, said rim-supporting rolls being so positioned as to prevent the web of a wheel from being rolled thereby, and means for moving all of the tread-working rolls in the same direction for changing their positions with respect to the rim-supporting rolls, whereby the rim of a wheel may be initially rolled between the rim-supporting rolls and one of said tread-working rolls and thereafter rolled between all of said tread-working rolls independently of and away from the action of said rim-supporting rolls, substantially as described.

25 3. In a machine for rolling the rims of car-wheels, the combination of a frame, a pair of sliding carriages mounted in said frame and movable toward and from each other, a main tread-working roll carried by one of said carriages having a working face corresponding to the tread and flange of a finished car-wheel, two or more similar tread-working rolls carried by the other of said carriages, a pair of rim-supporting rolls mounted in said frame

35 for supporting the rim of a wheel at the two sides of its web against the thrusting action of said main tread-working roll, said rim-supporting rolls being so positioned as to prevent the web of a wheel from being rolled thereby, and means for moving said carriages in the same direction for changing the positions of all of the tread-working rolls with respect to the rim-supporting rolls, whereby the rim of a wheel may be initially rolled between the rim-supporting rolls and the main tread-working roll, and thereafter rolled between all of said tread-working rolls independently of and away from the action of said rim-supporting rolls, substantially as described.

45 5. In a machine for rolling the rims of car-wheels, the combination of a frame, a pair of sliding carriages mounted in said frame and movable toward and from each other, a main tread-working roll carried by one of said carriages having a working face corresponding to the tread and flange of a finished wheel, two or more similar tread-working rolls carried by the other of said carriages, a pair of rim-supporting rolls mounted in said frame

55 for supporting the rim of a wheel at the two sides of its web against the thrusting action of said main tread-working roll, said rim-supporting rolls being so positioned as to prevent

the web of a wheel from being rolled thereby, means for moving said carriages in the same direction for changing the positions of all of the tread-working rolls with respect to the rim-supporting rolls, whereby the rim of a wheel may be initially rolled between the rim-supporting rolls and the main tread-working roll, and thereafter rolled between all of the tread-working rolls independently of and away from the action of the rim-supporting rolls, and means for positively driving all of said rolls, substantially as described.

75 5. In a machine for rolling the rims of car-wheels, the combination of three or more tread-working rolls having working faces corresponding to the tread and flange of a finished wheel, a pair of rim-supporting rolls for supporting the rim of a wheel at the two sides of its web against the thrusting action of one of said tread-working rolls, said rim-supporting rolls being so positioned as to prevent the web of a wheel from being rolled thereby, means for moving all of the tread-working rolls in the same direction for changing their positions with respect to the rim-supporting rolls, whereby the rim of a wheel may be initially rolled between the rim-supporting rolls and one of said tread-working rolls and thereafter rolled between all of said tread-working rolls independently of and away from the action of said rim-supporting rolls, and means for positively driving said rim-supporting rolls independently of the tread-working rolls, substantially as described.

6. In a machine for rolling the rims of car-wheels, the combination of three or more tread-working rolls having working faces corresponding to the tread and flange of a finished wheel, a pair of rim-supporting rolls for supporting the rim of a wheel at the two sides of its web against the thrusting action of one of said tread-working rolls, said rim-supporting rolls having their axes inclined downwardly toward their working ends and having end faces substantially at right angles to their axes, and means for moving all of the tread-working rolls in the same direction for changing their positions with respect to the rim-supporting rolls, whereby the rim of a wheel may be initially rolled between the rim-supporting rolls and one of said tread-working rolls, and thereafter rolled between all of the tread-working rolls independently of and away from the action of the rim-supporting rolls without rolling the web of the wheel, substantially as described.

In testimony whereof I have hereunto set my hand in presence of two subscribing witnesses.
